UNITED STATES PATENT OFFICE.

WILLIS E. HARMON, OF PORTLAND, MAINE, ASSIGNOR, BY DIRECT AND MESNE ASSIGNMENTS, TO HORACE PURINTON CO., OF WATERVILLE, MAINE, A CORPORATION OF MAINE.

BRICK-MACHINE.

1,169,808.

Specification of Letters Patent.

Patented Feb. 1, 1916.

Application filed February 24, 1915. Serial No. 10,227.

To all whom it may concern:

Be it known that I, WILLIS E. HARMON, citizen of the United States, residing at Portland, in the county of Cumberland and 5 State of Maine, have invented certain new and useful Improvements in Brick-Machines of which the following is a specification.

This invention relates to improvements in 10 brick machines. It is designed to provide a power driven machine so constructed that, if, for any reason, the operation of the machine is obstructed while the power is on, some parts of the machine will yield, there- 15 by preventing damage to the machine.

It is further designed to provide a machine which is simple in construction and operation and which may be operated with great rapidity.

20 In the drawings herewith accompanying and making a part of this application Figure 1 is a perspective view of my improved brick machine; Fig. 2 is a side elevation with parts broken away to show the construction 25 of interior parts, some of the parts being omitted for clearness; Fig. 3 is a detail sectional view taken on line $x-x$, Fig. 1, of the mechanism for operating the mold carriage actuating lever; Figs. 4, 5, and 6 are 30 side elevations of the double cam, toothed disk and clutch, respectively, which operate said lever, and Fig. 7 is a detail view of the safety mechanism interposed between the power and the mold carriage to prevent in- 35 jury to the machine due to accidental obstruction to the normal movements of the carriage.

Same reference characters indicate like parts in the several figures.

40 In said drawings A is a hopper having discharge openings a in the bottom thereof. In said hopper is mounted suitable rotating agitators and mixing devices 2 and 3 attached to a vertical shaft 4 driven in any 45 convenient manner by power mechanism not shown. Below said hopper is a chamber 5. In one of the vertical walls 6 of said chamber is an opening 7, in the front of which is placed a guide plate 8, preferably curved. 50 Adjacent said openings and forming a part of said chamber is a press box 9 having a cover 10 on the front of which is a plate 11 which is adapted to move just inside the plate 8. In the bottom of the chamber is a

series of discharge openings 12 which are 55 substantially the size of a brick. On shaft 4 and within chamber 5 are paddles 5^a which tend to convey the material toward said discharge openings. Adapted to reciprocate below the press box and chamber is a mold 60 carriage 13 upon which the brick molds are secured, the reciprocation of said mold carriage being effected by mechanism herein- 65 after described. The mold carriage carries a horizontal raised plate 14 which closes the discharge openings when the carriage with the molds are withdrawn.

The parts heretofore described are substantially the same as in the brick machines in common use and form no part of my in- 70 vention.

Secured to one side of the machine frame B, preferably in a bracket 15 is a rotatable shaft 16 adapted to be driven continuously by power mechanism not shown. Upon this 75 shaft is loosely mounted a double cam 17—18. Keyed on said shaft outside said cam is a notched disk 19. Outside said disk is a slidable clutch member 20. Pivoted at- 80 tached to the outside of the cam is a pawl 21, the free end of which is constantly impelled toward and into locking engagement with said notched disk by a spring 22, but is held normally out of engagement therewith by a roll 23 on the pawl 21 which normally is in 85 the path of clutch 20. The clutch is operated by a lever 24 attached at one end to a bracket 25 on the frame by a pivot pin 26 passing through a slot in the end of the lever. Intermediate the pivot and handle ends the 90 said lever is attached to the clutch by a pivot pin 27. A spring 28 attached to the frame and to the clutch operating lever is designed to automatically return the slidable clutch to disengage the pawl from disk 19 and stop 95 the machine after each mold has been pressed.

Pivotedly mounted on a post 29 on the side of the machine is an oscillating lever 30 terminating above the pivot point in di- 100 verging arms 31—32, each provided with a cam roll 33 located in the path of cam 18.

Below the mold carriage and secured to the frame is a rotatable shaft 34 upon which is rigidly mounted a crank 35. In the free 105 end of crank 35 is a bearing 36 having a vertical arm 37. On this bearing is an antifriction roll 38.

Pivots secured to the end of lever 30 is a link 39 which rests yieldingly upon anti-friction roll 38, said link being provided with a recess 66 with inclined sides to give entrance to a portion of said roll. The link 39 is held yieldingly in engagement with said roll by means of a clamp 41 slidably mounted upon said arm 37. The clamp is provided with a depending arm 42 having a slot 43 to admit the bearing 36 and with a depending flange 44 which extends far enough to engage and hold the link against lateral displacement. The tension of the clamp is regulated by a spring 45 interposed between the clamp and adjusting nut 46. An antifriction roll 40 is mounted in the clamp, as seen in Fig. 7, to engage the upper edge of the link, if desired, to prevent binding and to clear away hardened clay that might collect on the upper edge of the link.

On shaft 34 are rigidly mounted cranks 47 which are connected to the mold carriage by links 48. Mounted upon the frame above the press box is a shaft 49 to which is rigidly secured one or more cranks 50 which are connected by links 51 to the press box plunger 10 which serves both as a cover and press plunger.

Pivots mounted upon the side of the machine is a lever 52 having an arm 53 extending rearwardly and provided with an antifriction roll 70 in the path of cam 17. Pivots mounted on shaft 49 is a crank 54, and connecting the ends of lever 52 and an offset block 55 forming a part of crank 54 is a link 71 which extends loosely through said block and has a regulating tension spring 56 interposed between said block and an adjusting nut 57 on the link. Rigidly secured on shaft 34 is a crank 58, and connecting said cranks 54 and 58 is a link 59, the connection of said link with crank 54 being made by means of a pin 60 set in said crank and projecting into a slot 61 in the end of the link. A friction belt 62 engages the hub of the double cam with sufficient tension to prevent movement of the cam on its shaft, due to gravity. A spring 64 forms a section of the belt and gives it a yielding tension. The ends of the belt are secured in a strut 65 on the bracket 15 and its tension can be adjusted by means of a holding nut 67. The mold carriage travels over anti-friction rolls 68.

The cover to the press box is provided with an air valve 69 which prevents the formation of a vacuum in the top of the box.

The operation of the machine will now be described.

In Figs. 1 and 2 the machine is shown in ready to start position. The clutch shifting lever is moved to the right until it passes beyond the roll on the pawl which then engages the notched disk and starts the machine. As the double cam revolves it moves

the carriage operating lever to the right which through intermediate mechanism carries the carriage with the molds under the press box to be filled and moves the slotted link down. As the double cam continues to revolve, at the proper time the back cam engages the roll on the press plunger operating lever which through intermediate mechanism forces down the press plunger into the press box and also crank 54. This forces the material into the molds. As the cam continues to revolve the front cam engages the other arm of the mold carriage operating lever and returns the carriage to the point of beginning and at the same time automatically raises the press box plunger by means of link 59 actuated by link 58 again to ready position, which completes the cycle of operation. If the free movement of the carriage is prevented for any reason, the link on the carriage operating lever will slide to and fro rendering it unnecessary to shut off the power to prevent injury to the machine. The antifriction roll in the clamp above the link aids the free movement of the link.

Having described my invention and its uses, I claim:

1. A brick machine, a press box having discharge openings in the bottom, a press box plunger and means for operating it, a mold carriage and means for imparting an oscillating motion to said carriage including as one of its elements a link arranged to slip when the strain exceeds a certain tension.

2. In a brick machine, a press box having discharge openings in the bottom, a press box plunger and means for operating it, a mold carriage, an oscillating mold carriage operating lever having two diverging arms each provided with a cam roll, a cam adapted to engage said rolls alternately and connecting mechanism intermediate said lever and mold carriage including as one of its elements a link arranged to slip when the strain exceeds a certain tension.

3. In a brick machine, a press box having discharge openings in the bottom, a press box plunger and means for operating it, a mold carriage, an oscillating mold carriage operating lever having two diverging arms each provided with a cam roll, a cam adapted to engage said rolls alternately and connecting mechanism intermediate said lever and mold carriage including a link having a recess, an antifriction roll normally seated in said recess and a yielding clamp arranged to hold said link yieldingly upon said roll, and to allow it to slip when the strain exceeds a certain tension.

4. In a brick machine, a press box having discharge openings in the bottom, a press box plunger and means for operating it, a mold carriage, an oscillating mold carriage operating lever having two diverging arms each provided with a cam roll, a cam adapt-

ed to engage said rolls alternately and connecting mechanism intermediate said lever and mold carriage including a link having a recess, an antifriction roll normally seated in said recess and a spring controlled clamp having an antifriction roll arranged to press with yielding tension upon the top of said link, whereby the link will slip between said

rolls when the strain exceeds a certain tension. 10

In testimony whereof I affix my signature in presence of two witnesses.

WILLIS E. HARMON.
